SIGN FOR DRIVE-IN CAMPING SITES

Howard J. Leichner and Floyd D. Leichner, both of
1510 N. Neil St., Champaign, Ill.

Filed Mar. 3, 1965, Ser. No. 84,060

Term of patent 14 years

(Cl. D1—12)

Fig. 1.

Fig. 4.

Fig. 2.

Fig. 3.

FIG. 1 is a front elevational view of a sign for drive-in camping sites embodying our new design, the rear being a mirror image thereof;

FIG. 2 is an elevational view taken from one end thereof;

FIG. 3 is an elevational view taken from the end opposite that shown in FIG. 2; and

FIG. 4 is a top plan view thereof.

We claim:

The ornamental design for a sign for drive-in camping sites, as shown and described.
